UNITED STATES PATENT OFFICE.

JOHN R. SCHRADER, OF NEW YORK, N. Y., ASSIGNOR, BY MESNE ASSIGNMENTS, TO
RAILWAY JOURNAL PACKING COMPANY, INC., A CORPORATION OF NEW YORK.

MATERIAL FOR APPLYING LUBRICANTS TO AXLE-BEARINGS, &c.

1,279,019.

Specification of Letters Patent. Patented Sept. 17, 1918.

No Drawing.

Application filed January 4, 1917. Serial No. 140,599.

To all whom it may concern:

Be it known that I, JOHN R. SCHRADER, a citizen of the United States, and residing in the city of New York, county of Bronx, 5 and State of New York, have invented certain new and useful Improvements in Material for Applying Lubricants to Axle-Bearings and Particularly to Journals of Railway Rolling-Stock, of which the following is a specification.

This invention relates broadly to materials used for packing bearings of various natures, but it particularly applies to packing employed in railroad locomotive and 15 car axles. It is the object of this invention to provide an improvement upon materials hitherto used or known for the purpose.

Many materials and devices have been invented for the purpose here contemplated, 20 but it is a sufficient commentary upon their utility to draw attention to the fact that practically all railroads continue to use simple waste packing, the same being merely ordinary wool or cotton waste or a mixture 25 of the two.

For a successful packing, two and only two characteristics are requisite, viz., that it shall feed a sufficient amount of oil or other lubricant to the journal or other bearing surface to adequately lubricate the same, and secondly, that it shall not hold against or bring into contact with the journal or 30 other bearing surface any abrasive element, since if this is done it will tend to cause excessive wear, friction etc. Such abrasive elements may be of two classes, either the dust, cinders and the like naturally accumulated during the operation, or some element 35 such as metal or rough fiber contained in the packing itself.

The ordinary waste now in general use is deficient in both of these aforesaid essential characteristics since it quickly settles into a sodden mass, upon the upper or contact surface of which foreign abrasive elements readily collect with the result that either it falls away from the journal entirely, thereby entirely failing to perform 45 its function as a conveyer of lubricant to the bearing or it collects on its surface many foreign matters, holds them in contact with the journal or other bearing, thus causing undue friction and the dangerous and costly 50 condition known as "hot-box."

Experience has shown that could these

two difficulties attendant upon the use of waste, be overcome, it would provide an ideal packing. Many efforts have been made to give the waste a resilience absent from its natural state, but in all cases the added 60 element or elements to produce this characteristic have thrown the experimenter on the other horn of the dilemma by introducing an abrasive element.

My experiments with various substances 65 promptly forced upon me the conclusion that the substance to be added must be vegetable in origin, absorbent in nature, soft and resilient. It must also be comparatively inexpensive and fibrous so as to combine and 70 readily intermingle with the cordlike fibers of the waste. After failures with many different substances I found that these qualities were all present in sea grass, the most satisfactory variety being that com- 75 mercially known as Canadian sea grass.

I have found that this sea grass alone, will give more satisfactory results than any other known packing where the strain is not too great, but for ordinary use I have found that 80 in practice the best results are obtained when the sea grass is mixed with from one to four parts of ordinary commercial woolen or cotton waste, the percentage of sea grass which may be successfully employed depending 85 upon the severity of the service to which the journal is subjected. A satisfactory mixture for general use is one part of sea grass to two parts of waste. The use of wool waste is more desirable than cotton or mixed cotton 90 and wool, although the latter two have been successfully utilized where the service was not too severe.

The manner in which this mixture operates may be briefly described as follows:— 95 The sea grass being resilient and non-compressible tends to hold up the waste and keep it in contact with the journal. The sea grass being highly absorbent also acts as a reservoir for the oil and feeds it to the waste 100 in a manner similar to that in which oil is fed through a wick in a lamp. Being resilient and non-compressible, the sea grass also holds the waste fibers somewhat apart thus allowing air to circulate through the pack- 105 ing and likewise permitting foreign substances such as dust and cinders to pass through the packing to the bottom of the journal-box. One additional advantage of the sea grass is worthy of note, viz., its pol- 110

ishing quality, as a result of which a journal which has been for a short time in contact therewith assumes a smooth and bright appearance.

5. I therefore claim—

1. A packing for journal boxes consisting of a mixture of commercial cotton and wool waste and a fibrous resilient absorbent vegetable element.

10. 2. A packing for journal boxes consisting of a mixture of commercial cotton and wool waste and a fibrous resilient non-abrasive vegetable element.

15. 3. A packing for journal boxes consisting of a mixture of commercial cotton and wool waste and a fibrous resilient non-abrasive absorbent vegetable element.

20. 4. A packing for journal boxes consisting of a mixture of commercial cotton and wool waste and resilient sea grass.

Copies of this patent may be obtained for five cents each, by addressing the "Commissioner of Patents, Washington, D. C."

5.. 4 packing for journal boxes consisting of a mixture of commercial cotton and wool waste and Canadian sea grass.

6. A packing for journal boxes consisting of a mixture of 66 $\frac{2}{3}$ % of commercial cotton 25 and wool waste and 33 $\frac{1}{3}$ % of resilient sea grass.

7. A packing for journal boxes consisting of a mixture of 66 $\frac{2}{3}$ % of commercial cotton and wool waste and 33 $\frac{1}{3}$ % of Canadian sea 30 grass.

8. A fibrous packing for journal boxes consisting of textile waste and a resilient marine grass combined therewith.

In witness whereof, I affix my signature 35 in the presence of two subscribing witnesses.

JOHN R. SCHRADER.
